UNITED STATES PATENT OFFICE.

FRANKLYN LUTHER KING, OF SEATTLE, WASHINGTON.

ROTARY SPICE-CABINET.

1,189,456.

Specification of Letters Patent.

Patented July 4, 1916.

Application filed December 10, 1914. Serial No. 876,510.

To all whom it may concern:

Be it known that I, FRANKLYN LUTHER KING, a citizen of the United States, residing at Seattle, in the county of King and State of Washington, have invented a new and useful Rotary Spice-Cabinet, of which the following is a specification.

The invention relates to improvements in revolving cabinets.

10 The object of the present invention is to improve the construction of revolving cabinets and to provide a simple, practical, efficient, and comparatively inexpensive revolving cabinet designed particularly for holding spices both in bulk and in receptacles, and adapted to afford a display of the receptacle and capable of being readily filled and of enabling the receptacles to be easily and quickly removed.

20 With these and other objects in view the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit 30 or sacrificing any of the advantages of the invention.

In the drawings:—Figure 1 is an elevation of a revolving spice cabinet constructed in accordance with this invention. Fig. 2 is 35 a vertical sectional view of the same. Fig. 3 is a horizontal sectional view through the upper section of the cabinet. Fig. 4 is an enlarged detail horizontal sectional view illustrating the construction of the compartments of the upper section. Fig. 5 is a detail sectional view illustrating the manner 40 of mounting the vertical pivotal spindle and showing the construction of the lower ball bearing.

45 Like numerals of reference designate corresponding parts in all the figures of the drawings.

In the accompanying drawings, in which is illustrated the preferred embodiment of 50 the invention, the revolving cabinet comprises in its construction a base 1, preferably of circular form, and adapted to be arranged upon the floor or other supporting

surface and having bolted or otherwise secured to its upper face at the center thereof 55 a floor flange 2 provided with a threaded opening 3 in which is screwed the lower end of a vertical pivot or spindle 4. The pivot or spindle, which is preferably constructed of tubular metal, is rigidly connected with the base by the floor flange 2, and it receives upper and lower independently revoluble sections 5 and 6 designed for holding spices, but the revolving cabinet may, of course, be employed for containing and displaying various other materials.

The lower receptacle, which is mounted upon a lower ball bearing 7, may be of any preferred construction and it is provided 70 with an annular series of bins or compartments 8, preferably equipped at the upper portion with inclined doors 9 hinged at the top and adapted to afford ready access to the bins or receptacle 8, which are designed 75 for containing spices in bulk. Any number of bins or receptacles 8 may, of course, be employed, and their top and bottom walls are preferably formed by a horizontal top member 10 and a horizontal bottom member 80 11 having central openings 12 and 13 for the pivot or spindle. The bottom member 11 extends from the spindle or pivot 4 to the periphery of the lower section, and the upper member 10, which is of less diameter 85 than the lower member, extends from the pivot or spindle to the upper ends of the hinged doors of the compartments.

The upper section, which is supported upon an upper ball bearing 14, consists of 90 a shell composed of horizontal top and bottom disks or members 15 and 16, and vertical connecting pieces or members 17. The top and bottom disks or members 15 and 16 have central openings 18 and 19 for the 95 pivot or spindle 4, and the said top disk or member has a periphery composed of an annular series of straight faces 20. The bottom disk or member, which is recessed at its periphery to form a supporting ledge 100 21, is provided at the back thereof with a peripheral portion 22 composed of an annular series of straight faces 23, corresponding with the straight faces 20 of the upper disk or member. The upper and lower terminals 105 of the vertical connecting pieces or members

17 are suitably secured to the straight peripheral faces 20 and 23 of the upper and lower disks or members.

The upper section is provided on its exterior with an annular series of exteriorly arranged vertical compartments 24, formed by vertically disposed T-shaped bars or members 25 extending upwardly from the ledge 21 to the top disk or member 15, and having their web portions 26 suitably connected to the shell of the upper section at the side edges of the vertical connecting pieces or members 17. The web portions 26 of the vertical bars or members 25 extend radially from the shell of the upper section and are spaced apart a sufficient distance to receive cans 27 or other suitable packages or receptacles containing spices or other material, and the laterally extending flanges 28, which are located at the outer edges of the webs 26, extend inwardly over the side portions of the outer faces of the receptacles and confine the same in the compartments 24. Any number of compartments 24 may be employed and they may be made of any desired length to provide a cabinet of the desired capacity. The laterally extending flanges 28 are cut away at the top and terminate short of the upper ends of the webs to provide entrances 29 for enabling the compartments to be filled from the top. The flanges and the web portions of the members 25 are cut away at the bottom to provide outlets 30 for the convenient removal of the receptacles at the lower ends of the compartments. The bottom receptacles rest upon the ledge 21 of the lower disk or member and the entire contents of the upper sections are exposed between the laterally projecting flanges of the vertical bars or members. When the compartments are filled, the top receptacles, which are located at the entrances 29, are prevented from falling out by the top 31 of the upper section. The top 31, which is preferably of conical form, is of greater diameter than the top disk or member 15, and projects outwardly beyond the annular series of exterior compartments, and it is provided at its periphery with an inclined annular supporting flange 32 having an upturned lower edge 33 which engages across the outer edges of the webs 26, at the upper ends thereof, the edge 33 extending entirely around the upper end of the section 5 to hold the top in place by friction, and by its own weight, and also to retain the receptacles 27 in the upper ends of the compartments.

60 The inclined flange 32 extends upwardly and outwardly as illustrated in Fig. 2 of the drawings, and the entrances or inlets 29, which are of a length slightly less than the length of the receptacles, permit the latter to be readily introduced into them in an in-

clined position, as illustrated in dotted lines in Fig. 2 of the drawings, without raising the top or cover 31. When the top receptacle is in position, its upper portion extends above the lower portion of the flange 32 of the top and is held against outward movement by the same.

The upper and lower sections of the cabinet are adapted to be readily rotated to bring any of the compartments to the front, and the ball bearings, which may be of any preferred construction, are shown in the drawings as consisting of upper and lower bearing plates 34 and 35 and an interposed series of antifriction balls 36, retained in place by a race member 37 consisting of a disk or plate provided with openings 38 for the reception of the antifriction balls. The upper and lower plates and the race member are provided with central openings through which the spindle or pivot passes.

What is claimed is:—

1. A cabinet of the class described including a shell provided with exterior vertically disposed compartments formed by approximately T-shaped bars or members arranged at intervals and having their laterally extending flanges at their outer portions, said flanges being cut away at the top to provide inlets or entrances of a size to receive one package, and a top having a peripheral portion adapted to receive the upper ends of the packages therebehind, without raising the top, when the packages are introduced upwardly through said inlets, and to hold the uppermost packages against outward movement when the compartments are filled.

2. A cabinet of the class described including a shell provided with exterior vertically disposed compartments formed by approximately T-shaped bars or members arranged at intervals and having their laterally extending flanges at their outer portions, said flanges being cut away at the top to provide inlets or entrances of a size to receive one package and a top provided with an inclined peripheral flange having an upturned lower edge extending across to the web portions of the bars or members at the upper ends thereof and arranged to receive and confine the uppermost packages in the compartments when the latter are filled without raising the top.

3. A cabinet of the class described including a shell comprising upper and lower members, the lower member being recessed at its periphery to form a supporting ledge and having an upper peripheral portion corresponding with the periphery of the upper member, vertically disposed approximately T-shaped bars spaced around the periphery of the shell to form intervening compartments and extending from the ledge to the upper member of the shell, said T- 130

shaped bars having their flanges cut away at their upper ends to form upper inlets or openings of a size to receive one package, and a top having a peripheral portion arranged to receive the packages in said inlets without raising the top, and to confine the uppermost packages in the compartment, when the latter are filled.

In testimony, that I claim the foregoing as my own, I have hereto affixed my signature in the presence of two witnesses.

FRANKLYN LUTHER KING.
